COKE OVEN DOOR

Louis Wilputte, New Rochelle, N. Y.

Application July 30, 1937, Serial No. 156,453

13 Claims. (Cl. 202—248)

The general object of the present invention is to provide an improved coke oven door for use in removably closing the ends of horizontally elongated coke ovens.

More specifically, the object of the invention is to provide an improved coke oven door of the known so-called self sealing type comprising a rigid metallic outer door element or frame section, an inner refractory plug section of the door and a suitably flexible metallic sealing element or section. In the closed position of such a door the plug section extends into and substantially fills an end portion of a coking chamber and the sealing member is in sealing engagement with a metallic door frame member forming a rigid, though preferably removable, part of the oven structure at the margin of the end of the corresponding coking chamber.

My improved door in its preferred form is characterized by the novel manner in which the bricks or refractory blocks forming the body portion refractory plug section of the door, and the means for directly supporting and holding said bricks or blocks in place, are formed and arranged. In a preferred form of the present invention the refractory block material extends about, and is interlocked with, and so supported by a metal post as to form a self sustaining unit, which is detachably connected to the metallic outer portion of the door by metallic parts engaging the top and bottom of said post.

In the accompanying drawings illustrating preferred embodiments of the invention:

Figure 1 is a side elevation of a portion of a coke oven battery;

Figure 2 is a vertical section on the line 2—2 of Figure 1;

Figure 3 is a section on the line 3—3 of Figure 1;

Figure 4 is an elevation of a portion of the door as seen from its inner side;

Figure 5 is a sectional elevation generally like Figure 2 with parts broken away and showing a modified construction;

Figure 6 is a perspective view of the door shown in Figure 5, with some of the door bricks broken away for illustrative purposes;

Figures 7 and 8 are perspective views of outer and inner portions respectively, of the door shown in Figure 6;

Figure 9 is a perspective view of the door brick supporting parts of the door portion shown in Figure 6, and,

Figure 10 is a perspective view of one of the

parts shown in Figure 9, as seen from a different viewpoint.

The coke oven illustrated in the drawings is one comprising horizontally elongated coking chambers A and heating walls B arranged side by side in a row in which the coking chambers alternate with the heating walls. The coke oven masonry is reinforced and supported at the sides of the battery by a metallic armor, shown as comprising a flash plate G at each heating wall end, 10 and a corresponding vertical buckstay D by which the flash plate is held in place. At each end of each coking chamber end is a door frame member E. The latter preferably, and as shown, is in the form of a one-piece casting extending 15 around the door opening, and of substantial horizontal depth measured in the direction of the length of the heating walls and coking chambers, the heating walls being recessed at their vertical corners as indicated at B' to receive inner portions of the corresponding door frame members E, each of which extend into the oven structure and provides a metallic lining for the corresponding coking chamber end.

As shown, each door frame member E is anchored in place by adjustable clamping connections between its sides and the adjacent buckstay members D. The clamping connections shown comprise parts d welded to the buckstay members, and clamping levers F and bolts G. Each clamping lever F engages the corresponding door frame member E at one end, and at its opposite end engages a corresponding part d and is subjected to a suitable clamping force by means of the corresponding clamping bolt G, which acts 35 between the lever F and the corresponding part d. In the construction shown, each door frame member E includes adjustable flange portions e at its sides which abut against adjacent edge portions of the adjacent flash plates G.

In the form illustrated in the drawings, each door comprises a rigid outer metallic frame section, which in the particular form shown, includes vertical channel bar members H at the opposite sides of the door, top, bottom, and one 45 or more intermediate cross frame members H', and other cross frame members H² and H³, the cross frame members being welded at their ends to the side frame members H. The cross frame members H² provide anchorages for the pivot pins I' on which are mounted door locking levers or latch bars I, which may be turned into and out of engagement with the latch hook members I² welded or otherwise suitably secured to the corresponding door frame member E, to thereby 50

55

lock the door to and unlock it from said door frame member. The cross frame member H^3 is provided for engagement by an operating part of the usual door handling machine (not shown) employed to move the door into and out of its normal closed position in which the door extends into the doorway.

The intermediate flexible plate section or element of the door in the form shown in Figures 1-3 comprises a one-piece part K of metal plate, which may be a quarter of an inch or so thick and includes a substantially flat body portion, which in the closed position of the door extends entirely across the door opening, and an integral inturned rim or flange portion K' at the margin of said body portion, which then engages the sealing surface E' formed on the corresponding door frame member E .

The plate member K is connected to and suspended from the outer frame section of the door at or adjacent the top of the door by means shown as including a horizontal shaft L , passing through and supported at its ends by heavy plate or lug parts welded to the head portions of the channel bars H forming the side members of the rigid outer door frame section. The shaft L also passes through openings in brackets or lugs K^6 secured to the upper portion of the plate K , said openings preferably being horizontally elongated as shown. The lugs K^6 are welded or otherwise secured to a horizontal channel bar K^7 secured to the plate K by bolts K^8 which pass through the base portion of the channel bar K^7 and through the plate K and through a flange M' of a casting or other heavy metal part M thereby secured to the plate K . The member M extends into the oven chamber when the door is in its closed position shown in Figure 2.

In order to distort the sealing member K to ensure proper engagement of its sealing edge K' with the sealing surface E' of the door frame member E , a plurality of screws N are mounted at suitably distributed points along the margin of the rigid outer frame section of the door. The head of each screw N engages a recess in a corresponding small pad or reinforcing part O welded to the outer side of the member K .

The intermediate sealing member or section and the clamping means employed to distort said sealing member form the subject matter of my British patent application No. 115/36 from which the present invention is divided.

The bricks or refractory blocks Q , Q' and Q^2 constituting the body portion of the plug section of the door are stacked up on a rigid supporting member R secured to the inner side of the body portion of the member K adjacent the lower end of the latter. As shown, the member R comprises a horizontal portion R' on which the brick parts are stacked, and which, in the normal closed position of the door, rests upon the door sill portion e' of the door frame member E . The member R also comprises an uprising portion R^2 adjacent the plate K and detachably connected to the latter by bolts R^3 . Advantageously also, the member R includes gusset or side plate portions R^4 at the opposite side edges of the door between which the brick parts at the bottom of the stack are received. The brick supporting portion R' of the member R is formed at its upper side with a recessed seat R^5 for a metallic post s . The latter extends to the top of the plug section of the door and has its upper end loosely received in a recess M^2 formed for the purpose in the part M . In the preferred construction shown, the post s

is of T bar cross-section with the base of the section at the side of the post remote from the sealing member K .

The brick parts Q , Q' and Q^2 are suitably shaped to interlock with one another and with the post s which they collectively surround. As shown, one brick part Q and one brick part Q' are located at each of a plurality of different levels and constitute the body portion of the plug section brickwork. One of the two parts Q and Q' at each level extends from one side of the plug section of the door into overlapping relation with the post S and into abutting relation with the other part of the pair, which is also in overlapping relation with the post S and extends to the opposite side of the door. As shown, each of the parts Q and Q' includes a portion q at the outer side of the door extending into proximity with the web or leg of T bar section of the post S and extending in front of the corresponding portion of the head of the post section. Each brick part Q' includes a portion at the inner side of the post extending past the latter.

The brick parts Q and Q' are each recessed to receive a corresponding portion of a corresponding brick part Q^2 by which the brick parts Q and Q' are locked in place about the post S . As shown, the bricks Q and Q' in each of two adjacent horizontal layers or courses, collectively form a horizontal channel extending from the inner side of the door to the adjacent side of the post S , and shaped to receive and be filled by a corresponding brick part Q^2 . Each brick part Q^2 is formed with flange portions or ribs extending horizontally in the direction of the door axis and projecting away from the top and bottom faces of the brick Q^2 at the side edges of the latter. Each brick Q^2 is thus in effect a tenon dovetail part interlocking with two brick parts Q and two brick parts Q' , all of which are thereby held against significant horizontal movement relative to the post S . Since in the normal manipulation and use of such doors the latter are maintained vertically or substantially so, it is not necessary to provide interlocking provisions preventing horizontal movement of the locking brick parts Q^2 away from the T bar S , between which and the inner face of the plug door section, each part Q^2 extends. Friction is sufficient to hold those parts in place, even though the plug section brick parts are not laid with mortar, which may or may not be used.

The particular door shown in Figures 1, 2 and 3 is a pusher side door, and is provided at its top with a casting h for the usual levelling bar opening or doorway ordinarily provided in pusher side doors. As will be apparent to those skilled in the art, the seat for the upper end of the post S might be formed by a recess in the casting h , but I consider it preferable to provide a special part M as shown, in which the upper end of the post has its seat. In the preferred construction illustrated, the top bricks Q and Q' and a portion of the interlocking brick Q^2 are above the top of the post S , the bricks adjacent the part M being specially formed or chipped away to provide space for that part. The details just mentioned and the differences in respect thereto between the coke side and pusher side doors are without real significance in so far as concerns the essentials and principles of the present invention.

The brick parts Q , Q' , and Q^2 are disposed so as not to interfere with some relative movement of the post and brick parts as the door is heated and cooled. To this end, cardboard of suitable

thickness may advantageously be interposed between the post S and the adjacent brick surfaces in the initial assembly of the door. To insure sufficient flexibility and freedom for adjustment 5 of the sealing member part K, the latter is suitably spaced away from the outer face of the plug section of the door, and to this end cardboard of suitable thickness may well be interposed between the plate K and the plug section of the 10 door in the initial assembly of the latter.

In the door construction illustrated in Figures 5 to 10 the intermediate section or plate KA has welded to its edges a sealing flange or strip K¹⁰ having its inner edge bevelled off at K¹¹ and a 15 plurality of adjustable clamping devices N¹⁰ are provided which connect the flexible door element KA to the rigid outer frame section HA.

In the construction of Figures 5-10, the flexible element is suspended from a shaft L carried by 20 the outer frame member, exactly as in the construction first described, but preferably the flanged bar K⁷ carrying the hinge lugs K⁶, is welded to the plate KA, or is secured to the latter by bolts or rivets separate from the bolts M¹¹, 25 which are employed to detachably connect to the plate the part M¹⁰, shown in Figure 8, which replaces the part M previously described. The plate member KA carries at its lower end a rigid brick supporting member R¹⁰, similar in its general 30 purpose, and shown as generally similar in form, to the part R of the construction first described. In the construction shown in Figures 5-10, however, the bricks forming the refractory portion of the door, do not bear directly against the 35 horizontal lower portion of the member R¹⁰, but on a removable casting plate T. The latter, as is plainly shown in Figures 9 and 10 is formed with a notch T' receiving the bar S in the assembled condition of the plug section of the door. 40 The plate T is also formed with notches T² in its opposite side edges which, in the assembled door, receive lugs or projections R⁶ of the member R at the bottom of the latter and thereby hold the plate T against horizontal movement 45 relative to the supporting casting R¹⁰. While the notch T' is shaped to permit free movement of the plate transversely of the bar into and out of its normal relation therewith in the assembled condition of the plug section, the plate T is 50 interlocked against movement relative to the bar by a transverse plate or foot part S¹⁰ welded to the lower end of the bar and normally received in a recess T³ formed in the underside of the plate T. The brick parts of the plug section shown in Figures 6 and 8 comprise brick 55 parts Q¹⁰ and Q¹¹ which may be exactly like the brick parts Q' and Q² previously described, and are similarly interlocked by brick parts Q². As shown in Figure 7 a specially shaped head brick

60 Q¹³ forms the top of the plug section of the door being recessed at its end side to receive the upper end of the bar S. The previously mentioned metallic part M¹⁰ is interposed between the head brick and the subjacent bricks which are recessed 65 to receive the plate and the latter has welded to its outer edge the previously mentioned bolts M¹¹ by which the plug section of the door is detachably secured to the intermediate flexible section or element of the door.

70 As will be readily apparent, the plug section of the door, except for the head brick Q¹³, may be readily assembled to form the unit shown in Figure 9 with the bar S vertically disposed, or, conveniently in some cases, with the bar S horizontally 75 disposed in an assembly rack or cradle

not shown, but adapted to facilitate the assemblage of the brick and metallic parts. The unit thus formed may be transported bodily as by means of a crane or hoist having a hook adapted to enter the hole S¹² formed for the purpose in 5 the upper end of the bar, the foot portion S¹⁰ then preventing down movement of the refractory blocks and plate T, relative to the post S. The plug section unit may thus be readily moved into and out of its normal position at the inner 10 side of the member KA. In the normal condition of the door, the plug section is held against horizontal movement relative to the casting R¹⁰ by the projections R⁶ of the latter received in 15 the notches T², while the top of the plug is anchored in place by the part M¹⁰, through which the bar S passes, and the bolts M¹¹ by which the part M¹⁰ is detachably secured to the member KA. The head brick may be readily put into place or removed to expose the hole S¹² in the 20 bar S when occasion requires.

The door shown in Figure 5 is intended for use at the coke side of the battery at which the coke is discharged, and hence does not include provisions such as the casting h of the pusher 25 side door construction first described, for a leveling bar or poke hole. As those skilled in the art will understand, the special features of each of the door constructions illustrated, may be used 30 equally well in a pusher side door, as shown in Figure 2, or in a coke side door as shown in Figure 5.

Certain novel features of coke oven door construction and arrangement disclosed, but not 35 claimed herein, are disclosed in one or the other of my prior applications, Ser. No. 977, filed Jan. 9, 1935, and Ser. No. 52,995, filed Dec. 5, 1935, the present application being in respect to a portion of its subject matter, a division of one of said prior applications and being a division of 40 the other of said prior applications in respect to the remainder of its subject matter. Accordingly, the present case may be termed a continuation-in-part of each of the two above mentioned 45 applications.

While in accordance with the provisions of the 50 statutes, I have illustrated and described the best forms of my invention now known to me, it will be apparent to those skilled in the art that changes may be made in the form of the apparatus disclosed, without departing from the spirit of my invention as set forth in the appended claims, and that in some cases advantageous use may be made of some features of the present invention without a corresponding use of other features. 55

Having now described my invention, what I claim as new and desire to secure by Letters Patent, is:

1. In a coke oven door of the plug type, a plug 60 section comprising a vertical metallic post of flanged bar cross section, a stack of brick parts through which said post extends in interlocking relation with said parts and a metallic outer door portion having inwardly extending projections 65 adjacent the top and bottom of the door, the lower projection extending beneath and supporting the weight of said stack and providing a seat for the lower end of said post and the upper projection providing a support for the upper end 70 of the post restricting horizontal but not longitudinal movement of the latter, each of said brick parts when out of engagement with other brick parts being movable transversely of said post away from the latter. 75

2. In a coke oven door, a plug section comprising a metallic post of flanged bar cross section, a stack of brick parts through which said post extends in interlocking relation with said parts, and a metallic outer door section having inwardly extending projections adjacent the top and bottom of the door, the lower projection extending beneath and supporting the weight of said stack and providing a seat for the lower end of said post, and the upper projection providing a support for the upper end of the post restricting horizontal but not longitudinal movement of the latter, said brick parts being spaced from said post sufficiently to permit relative movements as a result of the relative thermal expansion of the parts, and each of said brick parts when out of engagement with other brick parts being movable transversely of said post away from the latter.
20. 3. In a plug type coke oven door, a plug section comprising a vertical metallic post, a stack of brick parts through which said post extends in interlocking relation with said parts and a metallic door portion having inwardly extending projections in which the ends of the post are mounted, the lower projection extending beneath and supporting the weight of said stack, said brick parts comprising locking parts and side parts adjacent the side edges of the door, each of said side parts extending from the corresponding side edges of the door into proximity with the post and being interlocked by one of said locking parts with a side part extending into proximity with the post from the opposite side edge of the door.
35. 4. In a plug type coke oven door, a plug section comprising a vertical metallic post, a stack of brick parts through which said post extends in interlocking relation with said parts, and a metallic outer door portion having inwardly extending projections adjacent the top and bottom of the door in which the ends of said post are mounted, the lower projection extending beneath and supporting the weight of said stack, said brick parts comprising side parts at the opposite side edges of the door each extending from the corresponding side edge of the door into proximity with said post and locking parts between said post and the inner face of the door and each interlocking with side parts extending into proximity with said post from the opposite side edges of the door.
50. 5. In a plug type coke oven door, a plug section comprising a vertical metallic post, a stack of brick parts through which said post extends in interlocking relation with said parts and a metallic outer door portion having inwardly extending projections adjacent the top and bottom of the door in which the ends of the post are mounted, the lower projection extending beneath and supporting the weight of said stack, said post being of flanged bar cross section comprising a base portion extending in the direction of the inner face of the door and a web portion at the outer side of said base portion extending transversely to the inner face of the door, said brick parts comprising side parts at the opposite side edges of the door each extending from the corresponding side edge of the door into overlapping relation with the base portion of said post and locking parts between said base portion and the inner face of the door and each interlocking with side parts extending into overlapping relation with said post from the opposite side edges of the door.
75. 6. In a plug type coke oven door, the combination with an outer metallic door portion, of a self-sustaining inner plug section unit, comprising a columnar mass of refractory material, metallic reinforcing and supporting means for said mass including a post extending longitudinally through said mass, and means detachably securing said supporting means to said metallic door portion adjacent the top and bottom of said plug section.
7. A plug type coke oven door combination as specified in claim 6, in which said post is provided with a lateral projection supporting the weight of the mass of refractory material in the normal vertical position of the latter and in which said outer portion of the door comprises an inwardly extending plug supporting bracket at its lower end on which said projection is adapted to rest.
8. A plug type coke oven door combination as specified in claim 6, in which the said post has a lateral extension at its lower end adapted to support the weight of the refractory mass and in which the said outer portion of the door comprises a plug supporting bracket at its lower end adapted to extend into a coke oven doorway, and in which said bracket and the metallic supporting and reinforcing means comprises portions adapted to interlock to prevent their relative horizontal movements when said plug section is seated on said bracket.
9. A plug type coke oven door combination as specified in claim 6, in which said post has a lateral projection at its lower end and in which a plate-like metal part formed with a notch is normally interposed between the lower end of the mass of refractory material and said extension, with the post extending through said notch, said notch being shaped to permit movement of said plate transversely of said post out of engagement with said mass and extension, and in which said bracket and the metallic supporting and reinforcing means comprises portions adapted to interlock to prevent their relative horizontal movements when said plug section is seated on said bracket.
10. A plug type coke oven door combination as specified in claim 6, in which said post has a lateral projection at its lower end and in which a plate-like metal part formed with a notch is normally interposed between the lower end of the mass of refractory material and said extension, with the post extending through said notch, said notch being shaped to permit movement of said plate transversely of said post out of engagement with said mass and extension, and in which said outer metallic door portion includes a supporting bracket for said plug section unit extending beneath the latter, said bracket and plate having portions interlocking to prevent their relative movements in a horizontal direction.
11. In a plug type coke oven door, the combination with a self-sustaining outer metallic door portion of an inner plug section unit, comprising a columnar mass of refractory material, metallic reinforcing and supporting means for said mass including a post extending longitudinally through said mass, means adjacent the level of the bottom of said unit detachably connecting said reinforcing and supporting means, and transmitting the weight of the plug section to said outer door portion, and means adjacent the level of the top of said section preventing its horizontal movement relative to said outer door section.
12. A self-sustaining plug section unit adapted to be removably secured to the metallic outer portion of a coke oven door, said section comprising a metallic post adapted for detachable connections at its ends to said outer metallic door section, and having a lateral projection at its lower end, and a columnar mass of refractory material resting on said projection, and through which said

post extends longitudinally and thereby prevents lateral displacement of said mass and post.

13. A coke oven door including a removable self-sustaining plug section comprising a vertical metallic post having a lateral projection at its lower end, and a columnar mass of refractory material resting on said projection and through which said post extends longitudinally and there-

by prevents lateral displacement of said mass and post, a metallic outer door portion having a plug supporting bracket at its lower end on which said plug section is removably mounted, and a detachable connection between the latter and said post at the top of the latter. 5

LOUIS WILPUTTE.
